By Attorney.

UNITED STATES PATENT OFFICE.

JOSEPH DICK, OF CANTON, OHIO, ASSIGNEE TO THE JOSEPH DICK MANUFACTURING COMPANY, OF CANTON, OHIO, A CORPORATION OF OHIO.

PIPE-DOOR.

1,327,377.

Specification of Letters Patent.

Patented Jan. 6, 1920.

Application filed July 5, 1916. Serial No. 107,525.

To all whom it may concern:

Be it known that I, JOSEPH DICK, a citizen of the United States, residing at Canton, in the county of Stark and State of Ohio, have invented certain new and useful Improvements in Pipe-Doors, of which the following is a specification.

The invention relates to a door for pipes, such as the discharge pipe leading upward from the blower of a fodder cutter or the like, in which it frequently becomes necessary or desirable to gain access to the interior of the pipe for the purpose of removing or dislodging material which has been come caught in and has clogged the mouth of the pipe; and the objects of the invention are to provide in such a pipe, a removable door in which the upper edges of the opening in the pipe will be lapped by the upper end of the door plate, and to dispense with all hinging connections between the cover or door plate; so that no protruding edges or parts will be presented on the interior of the pipe which tend to catch material and thus prevent its free and unobstructed passage upward through the pipe; and which is very simple in construction and inexpensive.

The object of the invention may be attained by providing at the desired place in the pipe an opening, and a door-plate therefore slightly larger than the opening, the plate being cut away at each side to permit the upper portion to be inserted within the opening and to lap the upper inside edges thereof, and there being transversely aligned interfitting bearing notches in each side of the opening and plate upon which the plate is adapted to be rotated, and a turn button pivoted to the pipe immediately below the opening serving to lock the plate in position with the lower portion of the plate lapping the lower edges of the opening on the outer side of the pipe.

The invention thus set forth in general terms is illustrated in the accompanying drawings forming part hereof, in which—

Figure 1 is a front elevation of a fragmentary section of pipe, showing the door applied thereto;

Fig. 2, a side elevation of the same partly in section;

Fig. 3, a transverse section on line 3—3,

Fig. 1;

Fig. 4, a perspective view of the door plate;

Fig. 5, a front elevation of a pipe section showing a modified form of door; and

Fig. 6, a fragmentary side elevation of a portion of the pipe showing the opening without the door plate.

Similar numerals refer to similar parts throughout the drawings.

The door consists of a plate 1 adapted to close an opening 2 which is provided in a pipe 3 formed of sheet metal in any well known manner.

The opening 2 in the pipe, as shown in Figs. 1 and 2, is in the form of a quadrilateral figure and is so disposed that its diagonals extend longitudinally and transversely of the pipe; the upper side edges as well as the lower side edges of the figure being equal and the plate 1 is formed from a similarly shaped piece of metal slightly larger than the opening 2 and bent on one of its diagonals to conform to the shape of the pipe.

In order that the upper edges 2^a of the opening will not form a projection on the inner surface of the pipe which will tend to catch the severed material and thus obstruct its free passage upwardly through the pipe, the upper portion of the plate is adapted to be inserted within the pipe with its upper side edges 1^a lapping the inside edges 2^a of the opening, the lower portion of the plate remaining on the outside of the pipe with its lower side edges 1^b lapping the lower outside edges 2^b of the opening.

For the purpose of thus permitting the insertion of the upper portion of the plate within the opening in the pipe, the plate is cut away or notched at each side from its transverse diagonal upwardly, forming the vertical side edges 1^c and shoulders 1^d. The width of the plate between its vertical side edges 1^c is slightly less than the length of the transverse diagonal of the opening, so that the plate may be inserted through the opening until stopped by the shoulders 1^d engaging with the sides of the pipe 2, which shoulders together with the side edges 1^c form axial bearing notches 4, adapted to engage with the bearing notches 5 in the pipe formed by the side corners of the opening 2.

In order to permit the upper and lower lapped edges 1^a and 1^b of the plate to lie flat against the upper inside edges 2^a and the lower outside edges 2^b, respectively, of the opening, the upper and lower side edges of

the opening are separated or distorted laterally as at 6 at each of the notches 5 in the pipe to an extent substantially equal to the thickness of the plate. For this purpose the 5 pipe 3 may be cut a slight distance inward at the side corners of the opening to permit the upper side edges 2^a to be bent outward and the lower side edges 2^b to be bent inward; and the vertical side edges 1^c of the 10 cover plate may also be bent slightly inward immediately above the shoulder 1^a.

In placing the door plate in position to close the opening its upper portion is first 15 inserted transversely through the opening until the bearing notches 4 thereof engage with the bearing notches 5 in the pipe, as shown in Fig. 2, whereupon the plate may be freely rotated on its transverse axis; and by reason of the distortion of the upper and 20 lower side edges of the opening at the notches 5 the upper and lower edges of the plate may be easily closed flat against the edges of the openings 2.

For the purpose of locking the plate in 25 closed position, a turn button 7 is pivotally mounted on the pipe 3 immediately below the opening 2, which button when rotated to engage the lower end of the plate, serves to hold it from rotation on its bearings and to 30 prevent it from slipping downward out of position; and if desired, the lower end of the plate may be cut away as at 8, in order to provide a larger bearing surface for the turn button.

35 In Fig. 5, I have illustrated a modified form of door, the door plate 1 and opening 2 being circular in form; so that it will be understood that the particular shape of the door which has been described is not essential to the invention. When this form of door is employed, the lateral incisions 6^a form bearing shoulders for the shoulders 1^a in the sides of the plate, but it will be evident that when the door is in the form of a 40 quadrilateral figure, the shoulders formed by the notches 5 at the angles of the upper and lower side edges of the opening will make the use of the lateral incisions, for this purpose unnecessary, in 45 which case the distortions are provided for convenience in order to more readily permit the lapping edges of the plate to lie flat against the pipe.

I claim:

50 1. A pipe having an opening therein, and a door plate slightly larger than the opening cut away at each side to permit its upper portion to be inserted in the opening

to underlap the upper portion thereof, there being inter-engaging shoulders at each side 60 of the opening and the plate, and means for holding the shoulders in engagement.

2. A pipe having an opening therein, with a bearing notch at each side, a door plate slightly larger than the opening cut away at 65 each side to form shoulders for engaging the notches and to permit its upper edge to be inserted in the opening to underlap the upper edge thereof, and means for holding the shoulders in engagement with the 70 notches.

3. A pipe having an opening therein, with a bearing notch at each side, a door plate slightly larger than the opening cut away at 75 each side to form shoulders for engaging the notches and to permit its upper edge to be inserted in the opening to underlap the upper edge thereof, the notches being slightly distorted to permit the edges of the plate to lie 80 flat against the edges of the opening, and means for holding the shoulders in engagement with the notches.

4. A pipe having an opening therein, and a door plate slightly larger than the opening 85 cut away at each side to permit its upper portion to be inserted in the opening to underlap the upper edge thereof, there being interengaging fulcrum notches at each side 90 of the opening and the plate for positioning the plate with its edges lapping the edges of the opening, and means for holding the notches in engagement.

5. A pipe having an opening therein, and a door plate slightly larger than the opening 95 cut away at each side to permit its upper portion to be inserted in the opening to underlap the upper edge thereof, there being interengaging fulcrum notches at each side 100 of the opening and the plate for positioning the plate with its edges lapping the edges of the opening, and means for locking the plate in closed position.

6. A pipe having an opening therein, and a door plate slightly larger than the opening 105 cut away at each side to permit its upper portion to be inserted in the opening to underlap the upper edge thereof, there being interengaging fulcrum notches at each side 110 of the opening and the plate for positioning the plate with its edges lapping the edges of the opening, and a turn button for abutting the lower edge of the plate having a flange for overlapping said edge to lock the plate in closed position.

JOSEPH DICK.
